CLAIM

We claim the ornamental design for a pivoting transaction device, as shown and described.

DESCRIPTION

FIG. 1 depicts a perspective view of a pivoting transaction device in a first position.

FIG. 2 depicts a front view of a pivoting transaction device in a first position.

FIG. 3 depicts a back view of a pivoting transaction device in a first position.

FIG. 4 depicts a left-side view of a pivoting transaction device in a first position.

FIG. 5 depicts a right-side view of a pivoting transaction device in a first position.

FIG. 6 depicts a top-side view of a pivoting transaction device in a first position.

FIG. 7 depicts a bottom-side view of a pivoting transaction device in a first position.

FIG. 8 depicts a perspective view of a pivoting transaction device in a second position.

FIG. 9 depicts a front view of a pivoting transaction device in a second position.

FIG. 10 depicts a back view of a pivoting transaction device in a second position.

FIG. 11 depicts a left-side view of a pivoting transaction device in a second position.

FIG. 12 depicts a right-side view of a pivoting transaction device in a second position.

FIG. 13 depicts a top-side view of a pivoting transaction device in a second position.

FIG. 14 depicts a bottom-side view of a pivoting transaction device in a second position.

FIG. 15 depicts a perspective view of a pivoting transaction device.

FIG. 16 depicts an exploded view of a pivoting transaction device.

The broken line showing parts of the drawings is included for the purpose of illustrating use and environment and forms no part of the claimed design. FIGS. 17-32 depict the design in alternate environment.

FIG. 17 depicts a perspective view of a pivoting transaction device in a first position.

FIG. 18 depicts a front view of a pivoting transaction device in a first position.

FIG. 19 depicts a back view of a pivoting transaction device in a first position.

FIG. 20 depicts a left-side view of a pivoting transaction device in a first position.

FIG. 21 depicts a right-side view of a pivoting transaction device in a first position.

FIG. 22 depicts a top-side view of a pivoting transaction device in a first position.

FIG. 23 depicts a bottom-side view of a pivoting transaction device in a first position.

FIG. 24 depicts a perspective view of a pivoting transaction device in a second position.

FIG. 25 depicts a front view of a pivoting transaction device in a second position.

FIG. 26 depicts a back view of a pivoting transaction device in a second position.

FIG. 27 depicts a left-side view of a pivoting transaction device in a second position.

FIG. 28 depicts a right-side view of a pivoting transaction device in a second position.

FIG. 29 depicts a top-side view of a pivoting transaction device in a second position.

FIG. 30 depicts a bottom-side view of a pivoting transaction device in a second position.

FIG. 31 depicts a perspective view of a pivoting transaction device; and,

FIG. 32 depicts an exploded view of a pivoting transaction device.
